UNITED STATES PATENT OFFICE.

WALTER I. JUDY, OF MCKEESPORT, PENNSYLVANIA.

PRESSED-STEEL SHOVEL.

946,369.

Specification of Letters Patent. Patented Jan. 11, 1910.

Application filed September 24, 1909. Serial No. 519,433.

To all whom it may concern:

Be it known that I, WALTER I. JUDY, a citizen of the United States of America, residing at McKeesport, in the county of Allegheny and State of Pennsylvania, have invented certain new and useful Improvements in Pressed-Steel Shovels, of which the following is a specification, reference being had therein to the accompanying drawing.

This invention relates to shovels and blanks for making the same and one of the objects thereof is to provide a shovel in a manner as hereinafter set forth, which is simple in construction, durable and inexpensive to manufacture.

Another object of this invention is to construct a shovel of pressed steel, the shovel being made from a blank cut and bent to produce a shovel when properly shaped.

These and such other objects as may hereinafter appear are attained by the novel construction shown in the drawing, forming a part of this specification, wherein there is illustrated the preferred embodiment of the invention, but it is to be understood that changes and variations can be resorted to without departing from the scope of the invention.

In the drawings:—Figure 1 is a plan view of a shovel blank as cut from sheet metal in accordance with this invention. Fig. 2 is a rear elevation of the completed shovel. Fig. 3 is a front elevation of the same. Fig. 4 is a vertical sectional view of a portion of the shovel handle, and Fig. 5 is a transverse sectional view through the shovel handle showing the shovel blade in end elevation.

In the accompanying drawings the reference numeral 1 denotes the body of a blank, said blank being formed from a sheet of malleable steel. The body 1 has the upper end thereof reduced, as at 2, to form an extension 3, said extension having the corners thereof cut away, as at 4. The upper end of the body 1 is also provided with a rectangular opening 5 corresponding in width to the extension 3. The material bordering upon the upper edge of the opening 5 is slit, as at 6, said slits representing a continuation of the vertical walls of the opening 5 and providing a tongue 7 corresponding in area to the extension 3. The lower corners of the tongue 7 are cut away, as at 8, for a purpose that will hereinafter appear.

The lower end of the body 1 is enlarged, as at 9, and the vertical edges of said en-

largement incline slightly toward the free end thereof, the vertical edges of said enlargement being connected to the vertical edges of the body 1 by curved edges 10, 60 curved in a reverse order, these curved edges being adapted to serve functionally as stiffening ribs, as will hereinafter appear.

The blank is pressed and folded to provide a shovel, as shown in Figs. 2 and 3, said 65 shovel consisting of a tubular handle bar 11, a scoop shaped shovel blade 12 and a stirrup-shaped handle 13. The tubular handle bar 11 is formed by bending the vertical edges of the body 1 inwardly and the blade 12 is 70 formed by pressing the enlargement 9 adjacent to the vertical edges thereof, whereby these vertical edges will be curved, as at 14, and will be connected to the bar 11 by stiffening ribs 15. In pressing and shaping the 75 blade 12 a V-shaped rib is formed at the base of the tubular handle bar 11 said rib gradually tapering into plate 12. The stirrup-shaped handle 13 is formed by bending at right angles the upper vertical edges of 80 the body 1 and then bending the extension 3 and the tongue 7 to form a barrel 16 between the arms 17 of the handle. The corners are removed from the extension 3 and the tongue 7 whereby no trouble will be experienced in 85 bending said extension and tongue between the arms 17.

The manner in which the blank is shaped and pressed insures rigidity of the shovel and a saving of material without increasing 90 the weight relative to an ordinary shovel.

Having now described my invention, what I claim as new is:—

1. A blank for manufacturing shovels, comprising a body, said body having the 95 lower end thereof enlarged and adapted to form a blade, said body having the upper end thereof provided with an extension and an opening in alignment with said extension, the material bordering upon the upper edge 100 of said opening being slit to form a tongue adapted in conjunction with said extension to be bent to form a hand-grip, and said body adapted to have the longitudinal edges thereof bent to form a tubular handle bar. 105

2. A shovel formed complete of a single blank of sheet metal comprising a body-portion widened at one end to form an enlargement and reduced in width at its other end to form an extension, said body provided 110 with an opening and a tongue extending into the opening, the tongue and the extension

being adapted to be bent toward each other to form a hand grip and said body adapted to have its longitudinal edges bent toward each other to form the shovel handle, the 5 said enlarged portion of the blank adapted to have its edges bent so that the enlargement constitutes the shovel blade.

In testimony whereof I affix my signature in the presence of two witnesses.

WALTER I. JUDY.
